UNITED STATES PATENT OFFICE.

CHARLES MCK. SPARROW, OF BUFFALO, NEW YORK.

ROTARY PUMP AND ENGINE.

1,408,839.

Specification of Letters Patent.

Patented Mar. 7, 1922.

Application filed November 29, 1920. Serial No. 426,979.

To all whom it may concern:

Be it known that I, CHARLES MCK. SPARROW, of the city of Buffalo, in the county of Erie, State of New York, United States of America, a citizen of the United States of America, have invented certain new and useful Improvements in Rotary Pumps and Engines, of which the following is a specification.

10 This invention relates to pumps and motors of the type in which one or more pistons move in an annular chamber provided with an inlet and an outlet port and separated by an abutment member adapted 15 to permit the pistons to pass without permitting communication between the inlet and exhaust ports, and my object is to devise a pump or engine of this type which will be easy to construct, efficient in operation, 20 and which will possess great durability.

I attain my object by means of the constructions hereinafter described and illustrated in the accompanying drawings in which—

25 Fig. 1 is a side elevation of my improved pump with one side of the casing removed;

Fig. 2 a cross section of the same;

Fig. 3 a side elevation of part of the same showing the parts in a different position.

30 In the drawings like numerals of reference indicate corresponding parts in the different figures.

In the specification and claims I refer to the device as a pump, but it will be understood, of course, that like most rotary pumps, it may be used as well as a motor.

The pump comprises two main parts, a stator 1 and a rotor 2, which form between them an annular fluid space 3. The periphery of the rotor revolves against roller bearings 4 carried by the side members 5 of the stator. On the inner periphery of the rotor is formed the internal gear wheel 6. The central disk-shaped part 7 of the stator is 40 suitably recessed to receive the rotary abutment member 8, on the periphery of which are formed the gear teeth 9 meshing with the internal gear wheel 6 of the rotor. The abutment member is rotated by means of 45 the drive shaft 10 to which it is secured. The rotor carries one or more radial pistons 11, which are adapted to pass through a recess 12 in the abutment as the parts rotate. The proportioning of the abutment and rotor 55 and the shaping of the pistons form important features of my invention, as on them

depends the ease of manufacture and the efficiency of the device. The diameter of the pitch circle of the gear teeth 9 is exactly one-half of the diameter of the pitch circle 60 of the internal gear wheel 6. From this it follows that as the one part rotates on the other, any point in the pitch circle of the gear teeth 9 will move in a straight line radially of the rotor. The edges 13 of the 65 mouth of the recess 12 are therefore formed on the pitch circle of the gear teeth 9, and the faces of the pistons 11 are formed as planes radial of the rotor. The edges 13 will thus maintain contact with the faces of the 70 piston from the time they come into co-operation until they pass out of co-operation, as will be seen on reference to the drawings. The inlet port 14 and the outlet port 15 are symmetrically arranged with reference to 75 the axis of the shaft 10 of the abutment member and have their adjacent edges separated by a distance not substantially greater than the width of the recess 12, (see Fig. 3.) This point is of importance, as if 80 the recess overlaps the inlet and outlet ports, direct passage of the fluid from one to the other would take place, which would result in inefficient operation of the pump, whereas if the recess is materially less in width 85 than the distance separating the adjacent edges of the ports fluid will be trapped in the recess, and as the fluid is usually incompressible, the pistons entering the recess tend to exercise pressure on the fluid, which 90 is liable to burst the pump.

The operation of the device will be readily seen in view of the above description and on inspection of the drawings. The shaft 10 is suitably driven and the abutment member 95 thereby rotated. The abutment member, through the medium of the gears 6 and 9, actuates the rotor causing the pistons to travel round the fluid space 3. Fluid is thus drawn in through the inlet port and 100 expelled through the outlet port, the abutment member at all times preventing direct communication between the two ports. The pistons pass through the recess in the abutment member, the edges of which by contact 105 with the faces of the pistons assist in maintaining the seal when the extent of mesh between the gears is least as is necessarily the case when the recess 12 is passing the space between the adjacent edges of the two ports. 110 It will be understood, of course, that suitable packing will be employed wherever

necessary between contacting relatively moving surfaces as is usual in the art.

What I claim as my invention is:—

1. A rotary pump comprising a stator and 5 a rotor forming an annular fluid chamber between them; an internal gear wheel formed on the rotor; a piston connected with the rotor having its faces formed as radial planes; a rotary abutment member 10 partly received in the stator having a recess therein for the passage of the piston and having gear teeth formed thereon meshing with the internal gear of the rotor, the pitch circle diameter of said gear teeth being 15 exactly one-half of the pitch circle diameter of the internal gear; and ports in the stator leading into the fluid space at adjacent points.

2. A pump constructed as set forth in 20 claim 1 in which the edges of the mouth of the recess in the rotary abutment are adapted to maintain contact with the radial faces

of the piston as the latter passes through the recess.

3. A pump constructed as set forth in 25 claim 1 in which the adjacent edges of the ports are separated by a distance not substantially greater than the width of the recess.

4. A pump constructed as set forth in 30 claim 1 in which the edges of the mouth of the recess in the rotary abutment are adapted to maintain contact with the radial faces 35 of the piston as the latter passes through the recess and in which the adjacent edges of the ports are separated by a distance not substantially greater than the width of the recess.

Signed at Buffalo, N. Y. this 26th day of October, 1920.

CHARLES MCK. SPARROW.
